UNITED STATES PATENT OFFICE.

WILLIAM E. DEPP, OF BROOKVILLE, PENNSYLVANIA, ASSIGNOR OF ONE-HALF TO GEORGE W. STEWART, OF BROOKVILLE, PENNSYLVANIA.

SHIPPING-BOX.

No. 884,572.

Specification of Letters Patent. Patented April 14, 1908.

Application filed April 3, 1906. Serial No. 309,648.

To all whom it may concern:

Be it known that I, WILLIAM E. DEPP, a citizen of the United States, residing at Brookville, in the county of Jefferson and State of Pennsylvania, have invented a new and useful Shipping-Box, of which the following is a specification.

The invention relates to improvements in shipping boxes.

10 The object of the present invention is to improve the construction of shipping boxes, and to provide a simple, inexpensive and efficient box of great strength and durability, designed for holding various kinds of merchandise and adapted to ventilate the same, and capable of being knocked down or folded up for returning it in compact form to the shipper.

With these and other objects in view, the 20 invention consists in the construction and novel combination and arrangement of parts, hereinafter fully described, illustrated in the accompanying drawings, and pointed out in the claims, hereto appended; it being understood that various changes in the form, proportion, size and minor details of construction, within the scope of the claims, may be resorted to without departing from the spirit or sacrificing any of the advantages of the invention.

In the drawings:—Figure 1 is a perspective view of a foldable shipping box constructed in accordance with this invention, and shown arranged for use, the cover being open. Fig. 2 is a transverse sectional view of the same, the cover being closed. Fig. 3 is a detail horizontal sectional view, taken substantially on the line 3—3 of Fig. 2. Fig. 4 is a perspective view showing the shipping 40 box folded. Fig. 5 is a longitudinal sectional view of the same. Fig. 6 is a transverse sectional view, taken substantially on the line 6—6 of Fig. 5.

Like numerals of reference designate corresponding parts in all the figures of the drawings.

1. designates the bottom of the shipping box, which may be of any desired size to suit the character of the merchandise to be shipped, and which is designed for shipping all kinds of merchandise, especially the various classes of goods requiring ventilation. The bottom 1 is provided at its lower face with longitudinal cleats 2, which support the

bottom above the supporting surface for protecting the box. The cleats 2 extend outwardly beyond the side edges of the bottom to form supports for a pair of strips 3 and 4, which are arranged vertically edge-wise, and which have their upper edges located at different elevations to permit the sides 5 and 6 of the box to fold flat against each other, and also to provide a space to receive the ends 7 of the box. The ends 7 are connected to the bottom by means of hinges 8, secured to the upper face of the bottom, and to the inner faces of the ends at the lower edges thereof. The ends are adapted to fold flat against the upper face of the bottom, as clearly shown in Fig. 5 of the drawings.

The front upwardly extending strip 3 has its upper edge arranged substantially flush with the uppermost faces of the ends, when the latter are folded, and the front side 5 is secured to the front strip 3 by hinges 9, which are secured to the inner face of the strip 3 and to the inner face of the front side 5 at the bottom thereof. This permits the front side of the box to fold downwardly and inwardly upon the ends, and the said front side is adapted to lie flat upon the said ends. The rear strip 4 has its upper edge arranged substantially flush with the upper face of the front side, when the latter is folded, and the said rear side 6 is secured to the rear strip by means of hinges 10, arranged at the inner face of the rear strip 4, and secured to the inner face of the rear side 6 at the bottom thereof. This permits the rear side of the box to fold flat upon the front side.

The top or cover 11 of the crate or box is composed of two sections 12 and 13, which are connected together by intermediate hinges 14, arranged on the outer faces of the sections 12 and 13. The top or cover is connected with the rear side 6 by means of rear hinges 15, secured to the inner face of the said side 6 and to the lower face of the section 13 of the top or cover. The front section 12 of the top or cover is of greater width than the rear section 13, which is adapted, when the box is folded, to lie in the same plane as the rear side 6, and the exterior intermediate hinges 14 permit the front section to fold backward upon the rear section and the rear side.

The parts of the box are retained in their folded position by means of an end catch 16,

arranged at one end of the box and secured to the lower face of the bottom. The end catch 16 is constructed of a single piece of resilient sheet metal and consists of a vertical body portion 17, an integral attachment arm 18, and an integral lip or jaw 19. The attachment arm 18 is formed by bending the lower end of the body portion inwardly beneath the bottom of the box or crate and is secured to the lower face of the said bottom. The lip or jaw is formed by bending the upper end of the body portion inwardly, and it extends into the recess of the adjacent end of the crate when the latter is arranged for use. The body portion of the end catch 16 is of a length to permit the lip to engage the upper face of the cover, when the box or crate is folded, whereby the parts are retained in their folded position.

20 The front and rear sides of the box are provided at their ends with plates or keepers 20, which are substantially L-shaped, and which are secured to the sides of the box adjacent to the upper edges thereof. The plates or 25 keepers extend inwardly from the vertical end edges of the front and rear sides 5 and 6, and are provided with substantially horizontal slots 21, whereby they are adapted to be engaged by headed studs 22, which are 30 carried by the ends of the box. The front and rear sides of the box are recessed or grooved at 23, adjacent to the slotted portions of the plates or keepers, to enable the heads of the studs to pass back of the said 35 headed portions, as clearly shown in Fig. 3 of the drawings. The studs 22 are preferably formed integral with short straps or bars 24, which are secured to the inner faces of the ends of the box at the upper portions thereof.

40 When the ends of the box are swung upward from their folded position, the headed studs, which project laterally beyond the vertical side edges of the ends 7, are carried into engagement with the slotted plates or 45 keepers, whereby the sides and ends are interlocked and are held against outward movement while the box is being filled. The ends fit between the sides and also prevent the latter from swinging inwardly, and as the 50 contents of the box will prevent the ends from swinging inwardly, it is unnecessary to provide a locking device for this purpose.

The top or cover of the box is secured in its closed position by means of a spring catch 55 26, mounted on the front side of the box, and extending upwardly from the lower portion thereof, and provided at its upper ends with a lip or flange 27, arranged to project over

and engage the upper face of the front section of the top or cover.

60

The sides and ends of the box consist of frames and sheets 28 and 29 of wire netting secured to the frames. This provides a ventilated box or crate, but the improvements herein shown and described are applicable 65 to various forms of boxes and crates. When the ends are provided with the frames, as shown in the accompanying drawings, a space is provided to receive the projecting lip or jaw of the end catch, so that the latter 70 will lie close to the end of the box and not interfere with the handling of the same.

It will be seen that the shipping box or crate is exceedingly simple in construction, and that it is adapted to be folded compactly for returning it to the shipper.

75

Having thus fully described my invention, what I claim as new and desire to secure by Letters Patent, is:—

A folding box or crate comprising a bottom, sides and ends hinged to the bottom and foldable inwardly thereon and composed of frames and woven wire fabric secured to the inner faces of the frames and forming exterior recesses, a cover hinged to one of the 85 sides and foldable on the same, an end catch located at one end of the box or crate and constructed of a single piece of resilient sheet metal and consisting of a vertical body portion, an integral attachment arm formed by 90 bending the lower end of the body portion inwardly beneath the bottom of the box or crate and secured to the lower face of the said bottom, and an integral lip formed by bending the upper end of the body portion inwardly and extending into the recess of the adjacent end of the crate when the latter is arranged for use, said body portion being of a length to permit the lip to engage the upper 95 face of the cover when the box or crate is 100 folded, whereby the parts are retained in their folded position, and a vertical side catch consisting of a single piece of resilient sheet metal connected at its lower end with a bottom and having its upper end bent inwardly and arranged to engage the cover of the box or crate when the latter is arranged 105 for use.

100

In testimony, that I claim the foregoing as my own, I have hereto affixed my signature in the presence of two witnesses.
